(No Model.)

G. BEBB.

CARDING MACHINE.

No. 356,090.

Patented Jan. 18, 1887.

UNITED STATES PATENT OFFICE.

GEORGE BEBB, OF INDIANAPOLIS, INDIANA, ASSIGNOR TO GEORGE MERRITT
AND WORTH MERRITT, BOTH OF SAME PLACE.

CARDING-MACHINE.

SPECIFICATION forming part of Letters Patent No. 356,090, dated January 18, 1887.

Application filed July 29, 1886. Serial No. 209,481. (No model.)

To all whom it may concern:

Be it known that I, GEORGE BEBB, of Indianapolis, in the county of Marion and State of Indiana, have invented a new and useful 5 Improvement in Carding-Machines, of which the following is a specification.

My invention is an improved doffer-cleaner for carding-machines, and seeks to provide a simple construction by which to clean the dirt 10 and short fiber from the doffer, and to discharge the dirt and very short stock into a trough or other receptacle, while the longer fibers will be returned to the doffer, to be incorporated with the lap.

15 The invention has for further objects other improvements; and it consists in certain features of construction and novel combinations of parts, as will be described.

In the drawings, Figure 1 is a side elevation 20 of a part of a carding-machine provided with my improvements. Fig. 2 is a detail perspective view of a part of my improved cleaner. Fig. 3 is a diagrammatic view, part in section, showing the relation of the doffer, cleaner, 25 stripper, and trough. Fig. 4 is a perspective view, showing a cleaner of different construction from that shown in the other figures; and Fig. 5 shows a cleaner of still different construction.

30 In carrying out my invention I employ a framing, constituting a support for the several operating devices, and such framing is shown as consisting of a standard, A, brackets B C, and carriers D and E. The standards A have 35 right-angled feet *a* at their lower ends, and such feet are slotted at 1 to receive the bolts 2, by which the standards may be secured adjustably to the framing of a carding-machine.

In the standards are formed vertical slots 3 40 and 4, to receive the bolts 5 and 6, which serve to secure the brackets B and C to the standards, so such brackets may be independently adjusted. These brackets B and C have slots 45 *b* and *c*, and the carriers D and E are secured to their respective brackets by bolts 7 and 8, passed through slots *b* and *c*, and thereby the said carriers may be adjusted independently of each other and of their brackets. I provide the carriers D and E with ears *d* and *e*.

50 The cleaner F is journaled in a box, G, which is supported by screws H H, threaded through

the ears *d* of carrier D. In the construction shown in Figs. 1, 2, and 3 the cleaner is a roller, having longitudinal rows *g* of card-clothing, and in practice such card-clothing moves into contact with the doffing-roller. The shaft or trunnion of this cleaner is extended, and provided with a band-pulley, I, geared by a belt, *i*, with a pulley on the shaft of the doffer.

The stripper J is a revolving stripper, being a roller provided with card-clothing. This roller has its shaft *j* journaled in boxes K, supported by screws *k*, threaded through ears *e*. On the shaft *j* is fixed a pulley, L, geared by 65 belt *l* with a pulley, *m*, on a fancy, M, so the revolving stripper will be run at a higher rate of speed. This stripping-roller moves in contact with the cleaner, and close to but not in contact with the doffer. In front of this stripper—that is, on the side of same opposite the doffer—I arrange a trough or receptacle, N, for the dirt and short stock stripped from the cleaner. Between this trough and the stripper I arrange a dividing-plate, O. This may be a 70 plain upright strip, with its upper edge close to the stripping-roller; but it preferably is as shown, having one side curved to fit around the roller, while the other or front side is straight and forms a support for the box N. 75 This box is detachably connected by hooks and eyes with the plate O, which latter is connected adjustably with the bracket C by means of a bolt, *o*, passed through a plate, *o'*, extended from the dividing-plate, and through a slot, *e'*, 80 in the part E. The hooks and eyes connecting box N and plate O are usually arranged as shown most clearly in Figs. 2 and 3, the hook *m* being pivoted at one end to the box N, and constructed to engage the eye *n'*, supported on the plate O. This plate serves to 85 divide the dirt and short worthless stock from the long fibers, discharging the former into the trough, while the latter is carried on and delivered to the doffing-roller, when it may be 90 carried thereby and united with the lap being formed. In this operation it will be seen the centrifugal force will throw off the short stock and dirt from the revolving stripper, while the 95 long fibers will be retained till they have 100 passed the upper edge of the dividing-plate.

Instead of the roller-form of cleaner shown

in Fig. 1, the oscillating form shown in Fig. 4 may be employed. In this construction a shaft, P, is journaled in the boxes G, and has arms p, carrying a bar, Q, provided with card-clothing, and movable into contact with the stripper. This shaft also has a crank-arm, 9, connected by a pitman, 10, with a crank, 11, which crank may be extended from the shaft or axle of the doffing-cylinder. The stripping-roller, 10, it will be understood, runs at a high speed.

The cleaning-roller may be revolved in one or the opposite direction. If run in the direction indicated by the arrow, the cleaner should be run slower than the doffer; but if moved in the reverse direction it may be run as fast or faster than the doffer, as may be desired.

In Fig. 5 the cleaner shown consists of a number of approximately-radial arms having 20 card-clothed bars at their outer ends, and fixed on a common shaft, which in operation is to be revolved. The mechanism for revolving such shaft may be the same as that shown in Fig. 1 for revolving the shaft of the cleaner therein 25 shown, and it is not thought necessary to duplicate the illustration of such mechanism.

Having thus described my invention, what I claim as new is—

1. The combination of the doffer, a stripping-roller having card-clothing, supports whereby said roller may be held close to the doffer, operating means for said stripping-roller, a cleaner, and supports and operating means therefor, whereby said cleaner may be 35 actuated into contact with the doffer and the stripping-roller, substantially as and for the purposes specified.

2. In combination with the doffer of a carding-machine, a stripping-roller having card-clothing, adjustable bearings for said roller, a 40 cleaner movable into contact with said doffer and roller, and supports and operating means for said cleaner and stripping-roller, substantially as set forth.

3. The combination, with a cleaner, of a revolving stripper, and trough arranged adjacent to said stripper, and a dividing-plate arranged between the receptacle of said trough and the revolving stripper, substantially as set forth.

4. The combination of the standard having 50 slots 3 and 4, the brackets B and C, bolts securing said brackets to the standard and passed through slots 3 and 4, and the cleaner and stripper supported on said brackets B and C, substantially as set forth.

5. The herein-described improved doffer-cleaner for carding-machines, consisting of the standard having slots 3 and 4, the brackets B and C, having slots b and c, bolts securing the brackets to the standards and passed through 60 the slots 3 and 4, the carriers D and E, having ears d and e, bolts whereby to secure said carriers adjustably to the brackets, the boxes G and K, adjustable connections between said boxes and the ears d and e, and the cleaner 65 and stripper journaled in such boxes, substantially as set forth.

GEORGE BEBB.
